CLOCK CASE

Alan E. Koplar, Chicago, Ill.

Application January 28, 1950, Serial No. 7,543

Term of patent 14 years

(Cl. D42—7)

To all whom it may concern:

Be it known that I, Alan E. Koplar, a citizen of the United States and a resident of Chicago, in the county of Cook and State of Illinois, have invented a new, original, and ornamental Design for a Clock Case, of which the following is a specification, reference being had to the accompanying drawing, forming a part thereof.

On the drawing:

Figure 1 is a front elevational view of the clock case, showing my new design; and

Figure 2 is an end elevational view thereof.

I claim:

The ornamental design for a clock case, as shown.

ALAN E. KOPLAR.
